UNITED STATES PATENT OFFICE

2,683,885

FLOOR CLEANING MACHINE

Ewing M. Johnson, Chicago, Ill.

Application October 21, 1949, Serial No. 122,784

3 Claims. (Cl. 15—50)

1

This invention relates to floor-cleaning machines and the like and has to do more especially with a machine for removing oil and similar liquids from floors and paved areas.

In various large industrial plants, as well as garages, where quantities of oil are employed there often is a great deal of accidental and unavoidable spillage, and much labor has heretofore been required to maintain floors and out-of-door paved areas in reasonably oil-free condition—it being a time-consuming job to thoroughly eradicate a large oil spot by hand labor and ordinary tools such as previously have been used for the purpose. And in addition to the very substantial labor cost often entailed in keeping the floors and like areas of a large industrial plant free of oil and other liquid combustibles, another factor of even greater importance is the increased fire hazard incidental to delay in cleaning up spillages.

The primary object of the present invention is to provide a power-operated machine which will rapidly and thoroughly remove oil and similar liquids from floors and like areas, and which is adapted to minimize the maintenance costs involved in the performance of such services, while at the same time speeding up the operation, thus reducing fire and industrial accident hazards.

Another object is to provide a self-propelled machine of the above-indicated character which can be driven under its own power from place to place, so that it is quickly available in all parts of a large industrial plant.

Still another object is to provide an improved floor-scouring rotary brush wherein the bristles are quickly renewable.

Additional objects and intrinsic advantages inherent to the present invention will be pointed out in conjunction with the ensuing detailed description.

While the most extensive use to which this invention is likely to be put is the removal of spilled oil from floors and similar areas, it is equally useful in the cleaning up of liquids other than oil, such for example as paint and molasses. Hence, the term "oil" as employed in this specification and the appended claims should be understood as broadly inclusive of all liquids of a more or less viscous nature.

In the drawings which accompany this specification:

Fig. 1 is a plan view of the machine;

Fig. 2 is a side elevation;

2

Fig. 3 is a sectional view taken at line 3—3 of Fig. 2;

Fig. 3a is a mechanical detail—the view being taken on line 3a—3a of Fig. 3;

Fig. 4 is a sectional view taken at line 4—4 of Fig. 1;

Fig. 5 is a rear elevation;

Fig. 6 is a sectional view taken at line 6—6 of Fig. 4;

Fig. 7 is a fragmentary sectional view taken at line 7—7 of Fig. 4;

Fig. 8 is a sectional view through one of the vertical rotary floor-scouring brushes and its driving mechanism;

Fig. 9 is a plan view of one of the vertical brushes;

Fig. 10 is a constructional detail taken at line 10—10 of Fig. 8; and

Fig. 11 is an enlarged section taken at line 11—11 of Fig. 8.

The various components of the machine are mounted, directly or indirectly, on a structural steel frame A of generally rectangular configuration, which, in turn, is supported on two rubber-tired front wheels 10 and 10' and a single rear wheel 12 which functions also as a rudder by means of which the machine is steered. Each front wheel 10, 10' is rotatably mounted on an individual trunnion 13, 13', which latter each are fixedly secured at one end to the frame A. The rear wheel 12 is attached to a yoke 14 to which is connected a vertical shaft 15 journaled at its upper and lower ends in bearings 16 and 17, respectively.

A small internal combustion engine B supported by the frame A and mounted at the top thereof supplies power both for propelling the machine and driving the several brushes.

Power is taken from the engine B through a transmission C and is transmitted by means of a drive chain 18 and a pair of sprocket wheels to a shaft 20 journaled in bearings 21 and 22.

A variable speed transmission D equipped with a manual gear-shifting lever 24 is connected to shaft 20 through the medium of a V-belt 25 and a pair of V-grooved pulleys 26 and 27. The belt 25 runs over an idler pulley 28 which normally applies enough tension to said belt so that it is operative to transmit power from shaft 20 to pulley 27. The idler pulley 28 is pivotally attached to the upper end of an arm 29—see Fig. 3—the lower end of which is pivotally connected to the machine frame; and a spring 30 biases the arm 29 clockwise, as depicted in Fig. 3, thereby

normally pressing the idler pulley 28 against the belt 25 to keep the same suitably taut.

A link 32 is pivotally connected at one end to the arm 29 and at the other end to the vertical arm of a bellcrank 33, which latter is fulcrumed at 34 to an arm projecting from the housing of transmission D and has a horizontal arm to the free end of which is connected a link 36—see Figs. 3 and 3a—the lower end of which link is connected to one arm of a bell-crank 37, the other arm of which is pivotally connected to one end of a foot-operated plunger 38, which is provided with a foot pedal 39 adapted to be depressed by the driver of the machine. The plunger 38 is slidably mounted in a bearing 40 and is urged outwardly by a coil spring 41. It will be apparent that when the pedal 39 is depressed, the arm 29 will be rotated clockwise, thereby moving the idler pulley 28 in the direction to tighten the belt 25.

The driving end of transmission D is connected to a differential gear within the housing 42 which, in turn, is connected to a pair of oppositely extending shafts 43 and 44 mounted within tubular housings 45 and 46, the outer ends of which are secured to brackets 47 and 48, respectively, rigidly attached to the frame A. Sprockets 50 and 51 are connected to the outer ends of the two shafts 43 and 44, and these are connected through drive chains 52 and 53 to driven sprockets 54 and 55, each of which is fixedly connected to one of the two front wheels 10 and 10'.

It will be evident that the machine is propelled through the above-described transmission system, which applies power to the front wheels when the plunger 38 is depressed by the operator. The transmission D includes a reverse gear and preferably also includes a plurality of forward speed gears.

A driver's seat E is mounted at the top of the frame and so positioned that the driver can easily reach all the controls; and a steering wheel F mounted on a vertical steering column 60 is positioned in front of the seat E within convenient reach of the driver.

The lower end of the steering column is provided with a sprocket 61, Fig. 1, which is meshed with a chain belt 62, the rear end of which is, in turn, meshed with a sprocket 63 on the vertical shaft 15. The chain belt 62 is crossed, as clearly shown in Fig. 1, and it consists of two lengths of chain 62a and 62b interconnected by a steel rod 64 and a turnbuckle 65 by means of which the chain belt can be suitably tightened. Rotation of the steering wheel and column in either direction obviously effects a simultaneous rotation of shaft 15 and rear wheel 12 in the opposite direction. Thus, when the steering wheel is turned to the right, when proceeding in the forward direction, the machine will turn to the right, and vice versa. The rear wheel 12 can be rotated about its vertical axis in either direction through an angle which enables the machine to turn about either front wheel as a center—which means that the machine can be turned around within a very small area.

Positioned at the front end of the machine is a group G comprising three rotary brushes identified, respectively, by reference numerals 70, 71 and 72—see especially Figs. 8-11. These comprise each a circular steel disc 73, welded or otherwise secured to a vertical tubular shaft 74 journaled in pillow blocks 75 mounted on angle irons 76 which are component parts of a fabricated structural steel carrier identified as a whole

by reference numeral 77. The carrier 77 is of rectangular box-like outline and is movable vertically, as a unit, within the frame of the machine. It thus serves as a support for the group of brushes G and as a medium by which said brushes are susceptible of being lifted and lowered at the will of the operator of the machine. The vertical guides for the carrier 77 consist of four angle irons 78—see Figs. 1 and 10—constituting integral parts of the frame A.

The three tubular shafts 74 each carry a chain sprocket 80, said sprockets being drivably interconnected by a chain belt 81 which, as shown in Fig. 1, passes around an idler sprocket 82 and so engages the sprockets 80 associated with the two outer brushes 70 and 72 that the latter rotate in opposite directions, as indicated by arrows on Fig. 1.

Power for driving the rotary brushes G is obtained from shaft 20 and transmitted through a V-belt 84 to a pulley 85 keyed to a shaft 86, which is journaled in a bearing 87 supported by the frame A—see especially Fig. 8. A bevel pinion 88 keyed to shaft 86 meshes with a bevel gear 89 which, in turn, is secured to the vertical shaft 74 which carries the brush 71. An idler pulley 91 attached to the lower end of an arm 92 pivotally connected at 93 to a component of the carrier 77 serves to maintain the belt 84 appropriately taut, under the tension of a spring 94. When the carrier 77 is elevated, as hereinafter described, the group of brushes G is kept in rotation by virtue of the fact that the idler 91 maintains the belt 84 under suitable tension, notwithstanding the change in elevation of the carrier, unless, of course, the engine is shut off or disengaged at transmission C.

The carrier 77, together with the brushes G and their driving gear are supported by a pair of chains 95, 95, the upper ends of which are connected to segmental sprockets 96, 96 keyed to a cross-shaft 97 journaled at its respective ends in bearings 98 bolted to the frame A. As most clearly shown in Fig. 4, the shaft 97 carries an arm 100 which is rigidly secured thereto, and to the distal end of which is pivotally connected a link 101, which interconnects the arm 100 with a manual operating lever 102 pivotally connected to the frame of the machine at 103. The lever 102 is positioned within easy reach of the driver; and when it is pulled back from the posture in which it is shown in Fig. 4 it rotates the shaft 97 through the medium of link 101 and arm 100 in the direction to elevate the carrier 77 together with the brushes G. When the lever 102 is pulled all the way back it acquires an over-center posture wherein it locks the carrier 77 and brushes G in elevated position. This is not illustrated in the drawings but is self-evident from inspection of Fig. 4.

Supported on the frame A directly above the group of brushes G is a hopper H—shown only in Figs. 2, 4 and 7—designed to receive a substantial quantity of oil-absorbent powder of the kind heretofore widely used for removing oil deposits from floors—usually calcined clay reduced to powder form; and said hopper has three bottom outlets 105 through which the absorbent powder is discharged in measured quantities. Fitted within each outlet 105 is a multi-bladed feed wheel 106—see Figs. 4 and 7—all three of which are mounted on and rotatable with a common shaft 107 extending lengthwise of the hopper and journaled in bearings attached to the hopper. One end of the shaft 107 is provided with a driven

sprocket 108 which is connected through the medium of a chain belt 110 to a driving sprocket 111, which latter is rotatably mounted on a trunnion secured to a bracket 112—see Fig. 7—and is integral with or fixedly coupled to a third sprocket 113, the teeth of which are drivably engaged by the drive chain 53 which drives the wheel 10'. It will be apparent that the shaft 107 and feed wheels 106 rotate whenever the machine is being driven either forward or in reverse; but powder is not necessarily discharged from the hopper whenever the machine is in motion for the reason that there is installed in the bottom thereof a shut-off plate 115, Fig. 7, which is manually movable lengthwise of the hopper and provided with three openings 116 through which the powder must gravitate enroute to the feed wheels 106.

Three flexible conduits 117 are connected each at its upper end with one of the outlets 105, respectively, and at their lower ends each with the upper extremity of one of the vertical shafts 74. From inspection of Fig. 7 it will be apparent that with shut-off plate 115 in the adjustment shown and the machine in motion, oil-absorbent powder is continuously fed downwardly from the hopper through conduits 117 and the bores of shafts 74, from the lower ends of which powder drops to the floor; and it will be further apparent that if the rotating brushes G are in contact with the floor, as illustrated, the floor will be thoroughly scoured and the oil mixed with the powder, so that subsequent removal of the oil-laden powder will leave the floor thoroughly clean. In order to insure that the entire floor strip traversed by the machine will be uniformly scoured, the three adjacent brushes should overlap, as viewed from the front or rear of the machine. This is clearly depicted in Fig. 1.

Situated rearwardly of the brush group G are two additional rotary brushes 120 and 121, constituting what is herein referred to as the brush group J. These are mounted on horizontal shafts 122 and 123, spaced apart lengthwise of the machine and journaled at their two ends in suitable bearings attached to a structural steel carrier 125 of generally rectangular form and constituted principally of angle irons. This carrier, like the previously-described carrier 77 supporting the brush group G, is positioned within a cage made up of four vertical angle irons 126 arranged in quadrature and forming component parts of the frame A. The said cage serves to position the carrier 125 in the horizontal plane and at the same time functions as a guide within which the said carrier is movable vertically as a unit.

A sheet metal housing 128 is mounted on the carrier 125 and encloses the brushes J at the top, ends and rear and includes a sloping top plate 129 which extends forwardly, as most clearly shown in Fig. 4, to overlie and form a cover for a box-like sheet metal receptacle 130 which rests on the frame of the machine and is removable therefrom laterally. The function of the brush group J is to pick up the oil-laden powder as the machine travels forwardly, and to discharge the same into the receptacle 130.

The carrier 125, together with the brushes J and housing 128, is suspended on four chains 132, the lower ends of which are attached to the top plate 129 of the housing 128 while their upper ends are connected to sprocket segments 133, two of which are affixed to a rotatable cross-shaft 134 while the other two are similarly affixed to a rotatable cross-shaft 135 journaled in bearings 136 carried by the frame of the machine.

As best shown in Fig. 4, an arm 138 attached to cross-shaft 134 is pivotally connected at its distal end to a link 139 which, in turn, is pivotally connected at its other end to the upper end of a lever 140 fulcrumed at 141; and an arm 142 similar to arm 138 is affixed to cross-shaft 135 and connected through the medium of a link 143 to the lower end of lever 140. Still another link 144 connects the upper end of lever 140 with the lower end of a hand lever 145 which is fulcrumed to the frame of the machine at 146. It will be evident from consideration of the above-described link-and-lever system that when the operator pulls the hand lever 145 the two cross-shafts 134 and 135 are simultaneously rotated in the directions effective to lift bodily the carrier assemblage, including the carrier 125, per se, together with the brushes of group J and the sheet metal housing 128.

The two group J brushes are driven in opposite directions, as indicated by the arrows thereon in Fig. 4, and the power for driving them is obtained from shaft 20 and transmitted through a pair of bevel gears 148 and 149, the former of which is secured to shaft 20—see Fig. 1—while the latter is secured to a stub shaft 150 journaled in a bearing 151 attached to the machine frame. The outer end of stub shaft 150 carries a sprocket 152, Fig. 2, which is drivably coupled to a sprocket 153 through the medium of a chain belt 154, said last-mentioned sprocket being secured to a shaft 155 journaled in suitable bearings, together with two V-grooved pulleys 156 and 158. A long V-belt 159 interconnects pulley 156 with a V-grooved pulley 160 attached to the outer end of brush shaft 122 and is held under suitable tension by an idler pulley 162 mounted on the free end of an arm 163 fulcrumed at 164 to the machine frame and biased upwardly by a coil spring 165, the upper end of which is anchored to the frame. A crossed V-belt 166 interconnects pulley 158 with a V-grooved pulley 167 attached to the outer end of brush shaft 123.

As the machine proceeds in the forward direction the strip of floor surface therebelow is progressively scoured by the brushes of group G, and the oil-laden absorbent powder is promptly swept up by the brushes of group J and deposited in receptacle 130.

One of the unique features of the subject invention resides in the co-operative action of brushes 120 and 121. It will be observed upon inspection of Fig. 4 that the oil-laden powder is propelled forwardly by brush 120 into receptacle 130 through a trajectory which overlies brush 121, but it may not be at once apparent why the powder is projected at such a high angle by brush 120 and not projected at a correspondingly high angle in the rearward direction by brush 121. The explanation which I believe to be correct is that the effective peripheral velocity of brush 121 is equal to its actual peripheral velocity less the velocity of the machine, whereas the effective peripheral velocity of brush 120 is equal to its actual peripheral velocity plus the velocity of the machine; and, in addition, the oil-laden powder is caused by the action of brush 121 to pile up in front of brush 120 so that the latter encounters a mass of considerable height, which serves to divert the projected powder away from the more or less horizontal trajectory which it otherwise would tend to follow. Whether or not the foregoing is an entirely accurate explanation of the conjoint action of the two brushes is not vitally important. The fact is that they

do the job and the disclosure is sufficient to enable those skilled in the art to duplicate the result irrespective of whether the foregoing theory of operation is correct or incorrect.

In the enlarged sectional view, Fig. 11, there is illustrated a novel feature of brush construction which I employ in the brushes of group G and which makes possible quick and economical renewal of the bristles while at the same time ensuring that the bristles are firmly anchored. As shown, each brush of group G comprises forty brush units 170, each including a tuft or bundle 171 consisting of a substantial number of stiff steel wires. The upper end portion of each bundle of wires is encased in a ferrule 172 comprising a pipe nipple having a pipe thread at each end; and to the upper end of the nipple is secured an internally threaded pipe cap 174. With the wires in place, as shown, the unit is inverted and dipped in molten metal such as babbitt or lead which occupies all the otherwise unoccupied space within the holder comprised of the ferrule and cap and firmly anchors the wires in place. And by way of further assurance against unintentional displacement, each wire is bent at its upper end, as shown in Fig. 11, to form a positive anchorage.

While I have illustrated and described but one embodiment of the invention, it will be immediately evident that there are many possible modifications within the scope and purview of my inventive concept. Accordingly, the invention should not be construed as limited except as plainly indicated by the terms of the appended claims.

Having described my invention and the mode of operation thereof, what I claim as new and wish to secure by Letters Patent is:

1. The combination in a machine for removing oil from a floor or the like, of a frame, wheels supporting the frame for movement along the floor, a first group of brushes located near the front end of a machine, said brushes each having a vertical axis of rotation, a carrier supporting said first group, said carrier being supported by the frame in a manner to enable vertical movement thereof for lifting and lowering the said first group of brushes, means carried by the machine for feeding oil-absorbent comminuted material onto the floor in position to be engaged by the said first group of brushes, a second group located rearwardly of said first group and comprising two rotary brushes having substantially parallel horizontal axes of rotation extending transversely of the machine, both said brushes of the second group normally resting on the floor, a carrier for said second group, said last-mentioned carrier being supported by the frame in a manner to enable vertical movement thereof for lifting and lowering the said second group of brushes, power means for driving both groups of brushes, the brushes of the second group being driven in opposite directions, the direction of rotation of the forward brush being such as to sweep the oil-laden material toward the rearward brush, and the direction of rotation of the rearward brush being such as to sweep the oil-laden material toward the forward brush, and a receptacle mounted on the frame and positioned to receive oil-laden material swept forwardly and upwardly by the rearward brush.

2. The combination in a machine for removing oil from floors or the like, of a frame, wheels supporting the frame for movement along the floor, a first group of rotary brushes located near the front end of the machine, said brushes being

rotatable in the horizontal plane and each mounted on a tubular vertical drive-shaft, a hopper for oil-absorbent comminuted material supported by the frame and positioned above said first group of brushes, conduits interconnecting said hopper with the bores of said drive-shafts individually, means operatively associated with said conduits for feeding regulated quantities of oil-absorbent comminuted material from the hopper to the bores of the respective drive-shafts and thence to the floor, a carrier supporting said first group of brushes, said carrier being supported by the frame in a manner to enable vertical movement thereof for lifting and lowering the said first group of brushes, an engine supported by the frame, a transmission interconnecting the engine with the said drive-shaft for driving the brushes of said first group, a second group located rearwardly of said first group and comprising two rotary brushes having substantially parallel horizontal axes of rotation extending transversely of the machine, both said brushes of the second group normally resting on the floor, a carrier for said second group, said last-mentioned carrier being supported by the frame in a manner to enable vertical movement thereof for lifting and lowering the said second group of brushes, power transmission means interconnecting said engine with said second group of brushes, the brushes of the second group being driven in opposite directions, the direction of rotation of the forward brush being such as to sweep the oil-laden absorbent material on the floor toward the rearward brush, and the direction of rotation of the rearward brush being such as to sweep the oil-laden absorbent material forwardly and upwardly, and a receptacle mounted on the frame and positioned to receive oil-laden absorbent material swept forwardly and upwardly by the rearward brush.

3. The combination in a machine for removing oil from floors and like areas, of a frame, a pair of drive wheels located near the front of the machine at either side thereof, a third wheel located at the rear of the machine and serving as a rudder, said frame being supported by the three wheels conjointly, a first group comprising a plurality of rotary brushes located near the front of the machine, said brushes each having a vertical tubular drive-shaft, a chain belt drivably interconnecting said drive-shafts, an engine mounted on the frame, a transmission interconnecting the engine with one of said drive-shafts, a carrier for said first group of brushes, said carrier being supported by the frame and adapted for vertical movement whereby to lift and lower the first group of brushes, a hopper adapted to contain a quantity of oil-absorbent comminuted material, said hopper being supported on the frame above the first group of brushes and having a plurality of outlets corresponding in number to the brushes of the first group, a plurality of conduits, each interconnecting one of said outlets with the upper end of one of said drive-shafts, individually, a plurality of feed wheels, each disposed in one of said outlets, individually, and operative when rotated to feed comminuted material from the hopper into the associated conduit, a feed wheel shaft mounting said feed wheels, drive means interconnecting said shaft with the engine, a second group located rearwardly of said first group and comprising two cylindrical rotary brushes having substantially parallel horizontal axes of rotation extending transversely of the machine, said last-mentioned brushes

being spaced apart lengthwise of the machine and both normally resting on the floor, power transmission means interconnecting said brushes of the second group with the engine and operative to rotate said brushes in opposite directions so that each brush is effective to propel loose material on the floor toward the other brush, a receptacle located forwardly of the said second group of brushes and positioned to receive loose material projected forwardly and upwardly by the rearward brush of the group, and manually operable means for elevating the brushes of the second group.
